(57) CLAIM

The ornamental design for a hair iron, as shown and described.

DESCRIPTION

FIG. 1 is a left-side perspective view of a hair iron in an open position.

FIG. 2 is a left side view thereof.

FIG. 3 is a right side view thereof.

FIG. 4 is a top view thereof; and,

FIG. 5 is a bottom view thereof.

The broken lines are for the purpose of illustrating the environment of the design only and form no part of the claimed design.
